Primary Examiner — Sandra S Snapp*Assistant Examiner* — Holly E Thurman(74) *Attorney, Agent, or Firm* — The Webb Law Firm(57) **CLAIM**

The ornamental design for a remote control cover, as shown and described.

DESCRIPTION

FIG. 1 is a front view of a remote control cover showing our new design;

FIG. 2 is a rear view thereof;

FIG. 3 is a bottom view thereof;

FIG. 4 is a top view thereof;

FIG. 5 is a right side view thereof;

FIG. 6 is a left side view thereof;

FIG. 7 is a front perspective view thereof;

FIG. 8 is a rear perspective view thereof; and,

FIG. 9 is a cross-sectional view thereof taken along lines 9-9 shown in FIG. 7.

The portions of the remote control cover shown in broken lines form no part of the claimed design.
